(57) **CLAIM**

The ornamental design for a vehicle-mounted aluminum tube telescopic mobile phone holder, as shown and described.

DESCRIPTION

FIG. 1 is a side view of a vehicle-mounted aluminum tube telescopic mobile phone holder embodying the new design;

FIG. 2 is another side view thereof;

FIG. 3 is a top view thereof;

FIG. 4 is a bottom view thereof;

FIG. 5 is a front view thereof;

FIG. 6 is a back view thereof;

FIG. 7 is a perspective view thereof;

FIG. 8 is a side view of the vehicle-mounted aluminum tube telescopic mobile phone holder with an arm part in extended position;

FIG. 9 is another side view of the vehicle-mounted aluminum tube telescopic mobile phone holder with an arm part in extended position;

FIG. 10 is a top view of the vehicle-mounted aluminum tube telescopic mobile phone holder with an arm part in extended position;

FIG. 11 is a bottom view of the vehicle-mounted aluminum tube telescopic mobile phone holder with an arm part in extended position;

FIG. 12 is a front view of the vehicle-mounted aluminum tube telescopic mobile phone holder with an arm part in extended position;

FIG. 13 is a back view of the vehicle-mounted aluminum tube telescopic mobile phone holder with an arm part in extended position; and,

FIG. 14 is a perspective view of the vehicle-mounted aluminum tube telescopic mobile phone holder with an arm part in extended position.
